United States Patent Office

Des. 192,646
Patented Apr. 24, 1962

192,646

LIGHT FIXTURE

Julio Pascucci, Meriden, and Henry S. Jones, New Canaan, Conn., assignors to The Miller Company, a corporation of Connecticut

Filed June 23, 1961, Ser. No. 65,695

Term of patent 14 years

(Cl. D48—23)

FIG. 1 is a perspective view of a light fixture showing our new design;

FIG. 2 is a side elevation thereof;

FIG. 3 is a bottom plan view thereof; and

FIG. 4 is an end elevation thereof as seen from the opposite end of FIG. 1.

What is claimed is:

The ornamental design for a light fixture, as shown.
